UNITED STATES PATENT OFFICE.

JOSEPH A. CHAPMAN, OF NORWICH, CONNECTICUT, ASSIGNOR OF ONE-THIRD
TO THOMAS E. RYAN, OF SAME PLACE.

KINK-PREVENTER FOR SILK-SPINNING MACHINERY.

SPECIFICATION forming part of Letters Patent No. 350,345, dated October 5, 1886.

Application filed June 16, 1884. Serial No. 135,073. (No model.)

To all whom it may concern:

Be it known that I, JOSEPH A. CHAPMAN, of the city of Norwich, county of New London, and State of Connecticut, have invented a certain new and useful Improvement in Kink-Preventers for Silk-Spinning Machinery, which improvement is fully set forth and described in the following specification, reference being had to the drawings which form a part of and accompany this specification.

My improvement consists in a certain device which, when attached to silk-spinning or "doubling and twisting" machinery as commonly constructed, will effectually prevent the kinking of the strand of silk while said machinery is stopped, my immediate object being to provide a device which shall be cheaply constructed and easily applied to spinning-frames now in use.

There has been much trouble experienced heretofore by the kinking of the strand of silk which remains exposed between the delivery-spool and the upper or receiving spool while the machinery is stopped or in the act of stopping, (as at the close of a day's work or during the noon hour,) and a considerable length of time must be spent each day in straightening such kinked portions before the machinery can be started. In straightening those strands which are kinked many of them are broken and must be knotted, thus reducing the quality and value of the work produced. My device is intended to overcome this serious difficulty, and to hold each thread at a uniform and constant tension while the machine is stopped.

Briefly stated, my invention consists, first, of a ring of plush or similar material, which surrounds and engages the upper flange of the delivery-spool, and, second, of mechanism for raising, lowering, and locking said device, as hereinafter fully described.

In the accompanying drawings, Figure 1 is a transverse sectional view of the principal parts of a double or two-sided spinning-frame, showing my new device properly applied. Fig. 2 is a top view of a section of the bolster-rail A, showing three spools with my new attachment applied. Fig. 3 is a detached view, somewhat enlarged, of one of my kink-preventers. Fig. 4 is a view of Fig. 3 from the back or inner side of the frame, showing the

means employed to secure the piece D adjustably to the rail e. Fig. 5 is a cross-section on line x x, Fig. 4. Fig. 6 is a detached view of one of the lever-arms q of Fig. 1.

In the annexed drawings, the letter A represents the upper or bolster rail, B the "step" or lower rail of a silk-spinning frame, and C the spindle which carries the spool E, said spool and spindle being rotated by the usual form of band, e, passing around the cylinder F.

Located immediately over the spindle C is a spool, G, on which the spun or twisted thread is wound, the arrangement of parts thus far named being identical with corresponding parts in spinning-frames as commonly used. (See, for example, Patent No. 156,525, dated November 3, 1874.)

On the back or inner side of rails A B are brackets a a', having holes through which slides, vertically, rod b, the downward movement of said rod being limited by the stoppins d, or, if preferred, by a collar secured adjustably to said rod, as shown at d'. Two or more of the vertical rods b should be used on each side of a frame.

Secured to and moving with the upper end of rod b is a rail, e, extending the entire length of the frame. Attached to this rail e are my devices for overcoming the tendency to kink, one for each spindle. Said devices are made, preferably, of wood or other light and cheap material, and substantially of the form shown at D in Figs. 2 and 3—that is to say, they are each provided with a central circular opening, which, when in place and properly adjusted, may slip down over the heads of the spools E, a narrow annular space being left between the flange of the spool and the inner wall of the wooden piece D. This space I fill by gluing or otherwise fastening to piece D a ring of soft or yielding material, preferably of plush, (see h, Fig. 3,) the nap on said plush engaging and resting lightly on the periphery of the spool-flange. The rail e and pieces D are lowered to the position shown in Fig. 1 after the machine is set in motion and remain in said lowered position below the lower flanges of the spools until it again becomes necessary to stop the machine, when said rail is elevated to the position indicated by the dotted lines in Fig. 1, and the spindles are then stopped in

the usual way. When the pieces D are raised to a level with the upper flanges of spools E, the strand *i* whirls around with said spool within the ring of plush, displacing the nap, 5 which acts as a continuous series of minute springs, each one of which, as strand *i* passes it, snaps back to its place ready for said strand when it makes its next round. When the spool E is stopped, these minute springs retain said 10 strand in a taut condition, instead of allowing it to slacken and kink, as it is inclined to do when it is not so supported. The ring of plush could, if so desired, be allowed to remain at all times in its elevated position and work 15 fairly well; but as I find it more convenient to remove the spools from the spindles when said ring is lowered out of the way, I have arranged my device with the vertical movement, as described.

20 Among the many materials which could be used (instead of plush) with very good results may be mentioned rubber, leather, velvet, woolen and worsted goods; but I find by actual experiments that plush gives the most 25 satisfactory results, and therefore prefer to use it.

Having thus described the device by which I prevent the kinking of the thread of silk, I will proceed to describe the mechanism which 30 I employ to move said device. It will be evident that each of the rails *e* could be raised and lowered independent of the other rail or rails of the same frame; but in order to save time I have so connected said rails with each 35 other that they work in unison—that is to say, when one of said rails is caused to move, all of the rails *e* of the same frame move at the same instant and in the same direction. Secured to the floor underneath the frame proper is a 40 frame, K, having bearings in which are located rock-shafts *k* *k'*, extending the entire length of the machine, and so connected by gears or segments of gears *m* at each end that a movement of one shaft will impart motion (in the 45 opposite direction) to the other shaft. Secured to shaft *k* is a lever, *n*, whose longer arm passes over shaft *k'*, reaching to a point nearly underneath the vertical rod *b*, it being connected with said rod *b* by a pitman, *o*. 50 The shorter arm of lever *n* extends downward, as indicated by dotted lines in Fig. 1, and also shown in the detached view Fig. 6. Shaft *k'* has secured to it a similar lever, *q*, whose longer arm reaches across shaft *k*, and 55 whose shorter arm is connected to the short arm of lever *n* by a stiff spring, *s*, the constant

tendency of said spring *s* being to bring the short arms together, and, in consequence, to carry the longer arms of said levers (and such parts as are connected with them) upward. 60

To hold the kink-preventing devices below the spools E while the machinery is in operation, I have provided a spring-latch, *t*, secured to the bolster-rail A. Said latch, as pieces D are forced downward, clasps one of said pieces, 65 (as shown in Fig. 1;) or, if preferred, said spring could be arranged to clasp the rail *e*.

In Fig. 1 I have shown latches *t* applied to both sides of the frame; but in practice I use said latch on but one side, so that when the 70 latch is withdrawn the kink-preventers on both lines of spindles are immediately thrown up into place on a level with the upper flanges of spools E, as above described.

Having thus described my invention, I 75 claim—

1. In combination with the spindle and spool of a spinning-frame, a ring of plush or other yielding material arranged to entirely surround and engage lightly the flange at the delivery end of said spool, the strand of silk passing upward between the plush and said spool, all substantially as and for the purpose specified. 80

2. In combination with the spindle and spool of a spinning-frame, a ring of plush or other yielding material arranged to entirely surround and engage the flange at the delivery end of the spool, and means, substantially as described, for elevating and depressing the 90 ring of yielding material, all substantially as set forth. 85

3. In combination with the spindle and spool of a spinning-frame, a ring of plush or other yielding material, the rail *e*, the rods *b*, supporting the latter, and means, substantially as described, for automatically forcing the rods 95 upwardly, substantially as set forth. 90

4. The combination, with the spindle and spool of a spinning-frame, of vertically-movable rods, a rail supported at the upper ends thereof, pieces attached to the rail and having openings, rings of plush or like material in said openings, means, substantially as described, for elevating and depressing said 100 rings, and a spring-latch, substantially as set forth. 105

JOSEPH A. CHAPMAN.
